(57) **CLAIM**

The ornamental design for cosmetic brush having a layered effect, as shown and described.

DESCRIPTION

FIG. 1 is a perspective view of a cosmetic brush having a layered effect according to an exemplary embodiment of the present design;

FIG. 2 is a right side elevational view of the cosmetic brush having a layered effect shown in FIG. 1;

FIG. 3 is a left side elevational view of the cosmetic brush having a layered effect shown in FIG. 1;

FIG. 4 is a rear elevational view of the cosmetic brush having a layered effect shown in FIG. 1;

FIG. 5 is a front elevational view of the cosmetic brush having a layered effect shown in FIG. 1;

FIG. 6 is a top plan view of the cosmetic brush having a layered effect shown in FIG. 1;

FIG. 7 is a bottom plan view of the cosmetic brush having a layered effect shown in FIG. 1;

FIG. 8 is a perspective view of a cosmetic brush having a layered effect according to an exemplary embodiment of the present design;

FIG. 9 is a right side elevational view of the cosmetic brush having a layered effect shown in FIG. 8;

FIG. 10 is a left side elevational view of the cosmetic brush having a layered effect shown in FIG. 8;

FIG. 11 is a rear elevational view of the cosmetic brush having a layered effect shown in FIG. 8;

FIG. 12 is a front elevational view of the cosmetic brush having a layered effect shown in FIG. 8;

FIG. 13 is a top plan view of the cosmetic brush having a layered effect shown in FIG. 8; and,

FIG. 14 is a bottom plan view of the cosmetic brush having a layered effect shown in FIG. 8.

(Continued)

The dashed lines in the drawings illustrate environmental structure and form no part of the claimed design.
